UNITED STATES PATENT OFFICE.

GEORGE SMITH, OF BALTIMORE, MARYLAND, ASSIGNOR TO ELLICOTT MACHINE CORPORATION, OF BALTIMORE, MARYLAND, A CORPORATION OF DELAWARE.

MOORING DEVICE FOR AIRCRAFT.

Application filed February 25, 1922. Serial No. 539,110.

To all whom it may concern:

Be it known that I, GEORGE SMITH, a citizen of the United States, residing at Baltimore, in the State of Maryland, have invented certain new and useful Improvements in Mooring Devices for Aircraft, of which the following is a specification.

This invention relates to mooring devices for air-craft, and particularly for dirigible balloons, of both rigid and non-rigid types.

The object of the invention is to relieve the envelope and frame work of the balloon of localized stresses.

The invention is particularly applicable to that type of mooring device in which a swiveling head is provided with a centering ring which receives the nose of the balloon and functions to maintain approximate alignment of the balloon, when the nose is held within the ring by means of a central mooring cable.

When a balloon is moored tightly to a device of this class while a strong wind is blowing, the cable must be put under heavy tension merely to draw the balloon into light contact with the ring. If the wind thereafter falls, the draft of the balloon on the cable is lowered and the stress of the cable on the balloon is resisted by pressure of the ring against the balloon. In the case of gusty winds the condition is even worse because of the repeated sudden shocks on the line of contact of the centering ring with the nose of the balloon.

In veering winds, also, the inertia of the swiveling head sets up heavy stresses which are resisted by the balloon at its line of contact with the centering ring.

The present invention provides a combined centering and buffing ring, which in its normal or unstressed condition offers a positive centering action, and which is nevertheless capable of yielding easily in the direction of stress exerted by the cable. In the preferred form, the centering ring is so mounted that its resistance to displacement rises at an ever-increasing rate as the displacement progresses.

A practical embodiment of the invention is shown in the accompanying drawing, in which—

Fig. 1 is a front view of the structure,

Fig. 2 is a side view of the same, partly in section,

Fig. 3 is a fragmentary section on an en-

larged scale showing how the buffing ring is mounted.

The usual mast is shown at 5. At the top of mast 5 is a head 6 mounted to swivel on a vertical axis, and provided with a guide 60 sheave 7 and trunnions 8. Mounted to rock in a vertical plane on the trunnions 8 is a yoke 9 provided with counter weights 10 at one end and a bearing 11 at the other. A passage 12 for the mooring cable extends 65 longitudinally through the bearing 11.

A hub 13 rotatable on bearing 11 carries a frame of generally conical outline, consisting of a circular girth 14, spreaders 15 and braces 16 for the spreaders.

The parts so far described follow, in their general form and arrangement, established practise. Instead of mounting an annular pad directly on the girth 14, as has been the usual practise, I mount the pad on a buffing 75 ring, which is movably supported in a special manner on the girth 14.

This buffing ring is shown at 17 and carries an annular pad 18. It is held by a plurality of radially arranged and hence mutually opposed tension devices indicated generally by the numeral 19, eight being shown in the drawing. Each of these tension devices 19 is pivotally connected to the ring 17 at 20 and to the girth 14 at 21.

As is best shown in Fig. 3 the tension device is of that type which acts when in tension to place a coil spring under compression. A cylindrical shell 22 pivotally connected at 21 to girth 14 houses a plunger 23 having a head 24. The plunger 23 is pivotally connected at 20 to ring 17. A coil spring 25 confined between head 24 and the end of shell 22 resists the withdrawal of plunger 23.

In the normal position of the parts, shown in Figs. 2 and 3, the axes of the tension devices 19 are all in one plane. The springs 25 are only slightly stressed, and act to hold the heads 24 against stops 26. This ensures 90 accurate and positive centering of ring 17, the spring devices then acting as struts.

The outline of the nose of the balloon is shown in broken lines at 27 and the balloon is moored by a bridle 28 (also shown in 105 broken lines), to which the mooring cable 29 is attached. The cable passes through the tubular guide 12, over sheave 7 and down through the hollow mast 5 to any suitable windlass (not shown). As ordinarily con-

structed such windlasses include a spring device to maintain the cable under tension and the invention is particularly, though not exclusively, adapted to use with windlasses so equipped.

If, in the case where a windlass is used not provided with a spring device, the balloon is moored to the device in a heavy wind, the relatively heavy stress on the cable will, 10 when the wind falls, draw the nose of the balloon slightly inward. If a spring device is used in the windlass the stress on the cable can be relieved only by considerable movement. In any event the ring 17 and pad 18 15 move bodily inward, relieving the stress on the balloon. If the balloon swings in a veering wind, the ring 17 will yield to accommodate the motion of the balloon until the inertia of the supporting structure is overcome.

The arrangement of the tension devices is such that the ring 17 moves inward for a considerable distance against a relatively slight spring resistance. This resistance increases at first at a very slow rate, because the tension devices are acting very nearly in the plane of the ring, and because during the first portion of the motion of the ring the springs 25 are only slightly stressed. In other words, the resistance to the motion of the ring is slight at first and for a considerable distance increases only at a very moderate rate. As the ring is progressively displaced, the resistance increases at an ever increasing rate and finally rises at a very rapid rate because of the fact that the spring devices have an ever increasing component in opposition to continued motion, a condition which results not only in an increased effective resistance, but in a rapidly increasing stress upon the springs 25. This arrangement, therefore, has particular advantage arising from the nature of the spring opposition to the movement of the buffing ring.

45 What is claimed is:—

1. The combination with a mooring device for air-craft, including a frame, and a cable adapted to be attached to the air-craft and serving to draw the air-craft toward the mooring device; of a buffing member resiliently mounted on said frame in position to engage said air-craft at a plurality of points aft of the nose thereof, said buffer having substantial range of movement in the direction of draft of said cable, different portions of said buffer being free to move unequally in such direction in response to unequal pressures exerted thereon by an air-craft.

60 2. The combination with a mooring device for air-craft, including a cable adapted to be connected to the air-craft and serving to draw the same toward the mooring device; of a buffing member movably mounted relatively to said mooring device and adapted to

engage an air-craft connected to said cable; and resilient means operably connected to said buffing member and opposing motion thereof in the direction of the draft of said cable, said resilient means being constructed 70 and arranged to offer relatively slight resistance to such motion through a considerable range thereof, with a rapidly increasing resistance near the end of its motion.

3. The combination with a mooring device 75 for air-craft, including a cable adapted to be attached to the air-craft and serving to draw the same toward the mooring device; of a buffing member movably mounted relatively to said mooring device and adapted to engage an air-craft connected to said cable; and a plurality of tension spring devices normally acting radially substantially in a common plane and serving to position said buffing member, said spring members exerting 80 a slight resistance to the displacement of said buffing member while the same is at or near its normal position, but exerting a rapidly increasing resistance when said buffing member is substantially displaced.

4. In a mooring device for air-craft, the combination of a support; a frame mounted on said support and capable of movement thereon to conform to the direction of air currents; a cable guided by said support and adapted to be attached to the air-craft to be moored and to draw said craft toward said support; a yielding spring mechanism mounted on said frame; and a combined centering and buffing member mounted on 95 said spring mechanism, adapted to engage said craft adjacent the point of attachment of said cable thereto and serving to maintain alinement of the craft with said frame and to receive the draft of said cable.

5. In a mooring device for air-craft, the combination of a support; a frame mounted on said support and capable of movement thereon to conform to the direction of air currents; a cable guided by said support and adapted to be attached to the nose of the air-craft to be moored and to draw said craft toward said support; a centering ring for engaging said air-craft aft of said nose and adapted to maintain the alinement of said 100 air-craft while receiving the draft of said cable exerted thereon through said air-craft; and a plurality of radially arranged spring devices supporting said ring in said frame, and capable of yielding to allow said ring 105 to move under the draft of said cable.

6. In a mooring device for air-craft, the combination of a support; a frame mounted on said support and capable of movement thereon to conform to the direction of air 110 currents; a cable guided by said support and adapted to be attached to the nose of the air-craft to be moored and to draw said craft toward said support; a centering ring for engaging said air-craft aft of said nose and 115

adapted to maintain the alinement of said air-craft while receiving the draft of said cable exerted thereon through said air-craft; a plurality of radially arranged spring devices supporting said ring and capable of yielding in tension to allow the centering ring to yield to the draft of the cable; and a series of stops serving positively to support said ring in said frame in its normal position.

7. In a mooring device for air-craft, the combination of a support; a frame mounted on said support and capable of movement thereon to conform to the direction of air currents; a cable guided by said support and adapted to be attached to the nose of the air-craft to be moored and to draw said craft toward said support; a centering ring for engaging said air-craft aft of said nose and adapted to maintain the alinement of said air-craft while receiving the draft of said cable exerted thereon through said air-craft; and a plurality of tension spring devices supporting said ring and each including a

positive stop serving to limit the contractile movement of such spring device, whereby the ring is positively positioned in its normal position.

8. In a mooring device for air-craft, the combination of a support; a frame mounted on said support and capable of movement thereon to conform to the direction of air currents; a cable guided by said support and adapted to be attached to the nose of the air-craft to be moored and to draw said craft toward said support; a centering ring for engaging said air-craft aft of said nose and adapted to maintain the alinement of said air-craft while receiving the draft of said cable exerted thereon through said air-craft; and a yielding spring support for said centering ring, which near its normal position exerts slight resistance to the displacement of said ring in the direction of draft of said cable.

In testimony whereof I have signed my name to this specification.

GEORGE SMITH.
